This invention relates to looms, and in particular to looms including whip rolls supported in movable bearing levers.

In contradistinction to the looms having a rigidly mounted roll the looms of the particular type contemplated herein are provided with yieldingly supported whip rolls thereby avoiding the drawback of the looms having a rigidly mounted roll which owing to its manner of support, cannot compensate the differences occurring in the warp length between the warp beam and the cloth beam and cannot therefore be used with a warp beam driven mechanically. The looms with a rigidly mounted roll are, of course, only suitable for use with simply braked warp beams from which the warp is drawn off intermittently and they have the disadvantage that with decreasing warp beam diameter, the braking moment has to be constantly reset manually, in which connection the coefficient of friction is itself a function, among other things, of atmospheric humidity and dust contamination, so that this setting can only be performed empirically, the more so as, in the absense of a component movable in dependence on the warp tension, it is also necessary to determine the warp tension, and thus the proper timing of the adjustment, manually, by touch.

The looms with yielding supported, or displaceable whip rolls which are known in the art, avoid some of these disadvantages, but the yielding support gave rise to a number of other drawbacks. Thus it was not possible to determine the extent of the yielding or spring effect which would meet all requirements. From the aspect of compensating the variations of the warp tension when the shed is opened and closed, a soft spring or cushioning action is advisable. A spring or cushioning action of this type, however, fails to meet the requirement that on impact of the batten the whip roll should be rigid and should even oppose the motion. Some attempts have already been made to solve this problem by increasing the mass of the whip roll which, however, as experience has shown, involves the danger that rolls begin to vibrate, thus affecting the warp tension in a completely uncontrollable manner.

A hard spring action on the contrary, is undesirable in the interests of compensating the shedding action on the warp tension and only partly prevents the whip roll from yielding on impact of the batten.

Furthermore, since the yielding or displaceably supported whip roll permanently changes its position according to the variations of the warp length between the warp beam and the cloth beam, it will be observed that the harder the spring action of the whip roll, the greater the differences in the warp tension arising during such changes in position.

The looms known in the art have, in consequence, the commonly shared, essential disadvantages that neither can the initial tension of the warp be kept even approximately constant, nor is it possible to set this initial tension to an absolute, predetermined value. As known to those skilled in the art, this initial tension however plays a decisive part in regard to the properties of the weave, and an essential requirement, particularly in regard to subsequent processing of the cloth, is not only that the loom should furnish cloths having the same, accurately predetermined, warp tension, but also that it should be pos-

2

sible to adjust a number of looms in such manner that this initial tension has the same, predetermined value in all cases.

Arrangements in which provision has been made for setting said initial tension have already been proposed. With these proposals in which for instance, springs with adjustable pretensioning are used, it is, however, neither possible to keep the initial tension constant, nor to set it to an entirely predetermined value. The reason for this inadequacy resides in the spring constant, since the force exerted by a spring is proportional to its deformation, as a result of which, this force depends on the position of a warp beam, i.e. is different in each case depending on the setting of the whip roll. For this reason, these proposals cannot possibly succeed in maintaining the initial tension of the warp constant since in looms with movably supported whip rolls, the position of whip roll depending on the free warp length between the warp and the cloth beams and which could determine the amount of feed of the warp beam, varies.

Thus the only means for the weaver of determining the initial tension has been as yet to judge by hand, with the best possible approximation and from his own experience, whether the warp tension is, or is not, correct for the particular cloth being made.

To keep the initial warp tension at least in large measure constant, in order to enable the warp tension to be brought under control in the manner indicated, it has already been suggested to carry the whip roll in movable supporting levers, thereby making it possible to track the free warp length between the warp and the cloth beam and to adjust the subsequent advance or feed of the warp beam in terms of this free warp length. In the known arrangements of the latter kind, however, it is not possible to prevent the initial tension of the warp from varying with the position of the whip roll. This follows, of course, from a mere consideration of the forces acting on the whip roll. It is a device, in which the displaceably supported unit comprises a single whip roll, the perpendicular distance from the warp thread coming off the warp beam to the pivot point of the assembly is denoted by "a" and that of the warp thread running onto the unit or whip roll by "b" (in a manner similar to that shown in FIG. 5), then the warp applies a torque to this assembly which is proportional to $a-b$, with the result that if, during the swinging displacement of the unit or whip roll "a" decrease, then "b" increases, i.e. the value $a-b$ and thus the initial tension of the warp varies very considerably. On account of this dependence of the initial tension of the warp on the position of the whip roll, it is naturally not possible to keep the warp tension approximately constant.

It is therefore an object of this invention to provide a device adapted to control and substantially maintain constant, the warp tension.

It is also an object of the invention to ensure the desired adjustment of the warp tension by means of a weight acting on rockable bearing means carrying a pair of whip rolls.

Another object of the invention resides in the provision of an assembly operated by said rockable bearing means to control the warp beam advance in accordance with the free length of warp.

A further object of the invention is to associate a damping or braking device with said controlling assembly to suspend temporarily its action on the warp beam, when the warp is suddenly subjected to an abrupt stress increase, for example upon impact of the batten.

Still further objects of the invention will become apparent from the following description.

One embodiment of the loom improved according to the

invention is represented diagrammatically and by way of example in the drawings annexed hereto.

In the drawings:

FIGS. 1 and 1a are two parts of a rear view of this embodiment;

FIGS. 2 and 2a similarly show a plan view thereof;

FIG. 3 is a side view, in the direction of arrow A in FIGS. 1 and 2;

FIG. 4 is a side view in the direction of arrow B in FIGS. 1a and 2a;

FIG. 5 is a diagrammatic representation of the motion gear of said embodiment;

FIG. 6 is a top view of a driving cam;

FIG. 7 is a diagrammatic representation of the cam control curve and

FIG. 8 is a section through a braking device incorporated in said embodiment.

In the drawings, the rear part of a loom is shown in which the warp beam 1 is supported for rotation between two bearing plates 3a and 3b on the machine frame 2. The warp beam is driven by a worm wheel 4 carried on the shaft 1a of the warp beam which meshes with a worm 6 carried on the shaft 5. The shaft 5 is connected through an overrunning clutch 7 with the drive pin 8, the overrunning clutch operating in the direction of rotation causing the warp to unwind from the warp beam. The purpose of the overrunning clutch is to transmit the rotary motion of the pin 8 to the shaft 5 in one direction of rotation only, viz. that of winding off the warp, there being the further possibility of releasing the clutch between the shaft 5 and the pin 8 so that the shaft 5 can be rotated in the desired direction by the handwheel 9. A bearing stool 10 is secured to the bearing plate 3a, in which the shaft or spindle 12 carrying the bevel wheel 11 is supported for rotation, the said bevel wheel meshing with a corresponding wheel 13 on the drive pin 8. On the end of the spindle 12 projecting beyond the front face of the bearing stool 10, a free rotary lever collar 14 is fitted having levers 15 and 16, integral therewith, whereof the first (15) coacts with the push rod 17 working synchronously with the loom batten, not represented, and the second (16) is hinged to the drive rod 18. On the same end of the shaft 12, a lever 19 is attached which in turn is connected with the control rod 20.

The double-plate bearing frames 21a and 21b which, among other things, serve to support the control shaft 22, the significance and operation of which will be presently described, are attached above the bearing plates 3a and 3b on the back of the loom to the frame 2. The arm 23 is screwed to the bearing plate 21a. This arm 23 has two pairs of eyes 24 each carrying a slide bar 25, on which slide bars the blocks 26 work movably. One end of the guide block 27 pivots on the pin 26a of this slide block, a pin 20a of the control rod 20 passing into this guide and being movably secured there while the drive rod 18 is connected to a fixed pivot 27a on this guide block 27. The pin 20a of the control rod 20 is held always at a constant distance from the center of the ring 30a which is supported for free rotation on the control shaft, by the ring 30a. On the end of the control shaft 22, projecting beyond the bearing plate 21a a pinion 31 is fixed which meshes with a rack bar 26b on the slide block 26. As a result of this, the pin 20a of the control rod 20 is pivotable on the one hand about the rotating pin 26a of the slide block 26 and on the other hand about the center of the ring 30a, the extent of the pivoting motion depending on the distance between the pins 20a and 26a, i.e. on the relative position of the slide block 26 with reference to the frame 2 or to the ring 30a, which relative position can be varied by moving the slide block 26. Such a displacement occurs when, in a manner subsequently described, the pinion 31 rotates and thus by way of the rack bar 26b moves the slide block 26 along the slide bar 25. If now the push rod 17, as stated, reciprocates synchronously with the loom batten, this reciprocating motion is transmitted by way of the lever 15, the lever

collar 14 and the lever 16 to the drive rod 18 which consequently swings to and fro synchronously, the guide piece 27 pivoting accordingly on the pin 26a of the slide block 26. The pin 20a of the control rod 20 also performs the same swinging motions with the difference that it reciprocates additionally in the slide block 26, since, on account of the lever 30, its distance from the center of the ring 30a cannot change. Since, in the position shown (FIG. 4) the pin 20a of the control rod 20 lies nearer the pivot pin 26a of the guide block 27 than the fixed pivot 27a of the drive rod 18, all referred to the motion phase shown, the transmitted reciprocating motions of the control rod will be of smaller amplitude than those of the drive rod 18. The value of this amplitude can be varied, however, by rotating the control shaft 22, the pinion 31 of which engages in the rack 26b of the slide block 26. In FIG. 4, the slide block 26 is shown in the mid position. If now there is a movement to the left in FIG. 4, then the distance from the pin 20a of the control rod 20 to the pivot pin 26a of the guide block 27 increases by the action of the lever 30, by which means the amplitude of the reciprocating motion of the control rod is increased, whereas a movement to the right again results in a reduction of this amplitude, which finally falls to zero if the pin 26a is at the same distance from the shaft 22 as the pin 20a. As a result of this, if, by means of the control shaft 22 or the pinion 31, the slide block 26 is moved, in each case depending on the direction of motion, there is a resulting increase or reduction in the amplitude of the motions of the control rod 20.

The oscillating motions of this control rod 20 are now transmitted through the lever 19, the shaft 12 and the bevel wheels 11 and 13 to the drive pin 8 and the overrunning clutch 7 from which, however, on account of the presence of the overrunning clutch, the further transmission of the motion takes place in one rotary direction only, viz. that corresponding to winding off the warp, through the shaft 5, the worm 6 to the worm wheel and thus to the warp beam shaft. As a result of this, by the reciprocating motions of the control rod 20, the warp beam shaft 1a is rotated stepwise, the amount of this rotation depending on the amplitude of the oscillating motion of the control rod. This amplitude is, however, also a function of the position of the rotating pin 20a of the control rod within the guide block with reference to its pivot point, viz. the pin 26a of the slide block 26. If, consequently, starting from the position shown in FIG. 4, the slide block is moved to the left by means of the pinion 31 and the rack bar 26b by suitably rotating the control shaft 22, then the forward steps of the warp beam increase in magnitude, from which it is already clearly evident that the said rotation of the feed shaft must occur with decreasing diameter of the warp wound on the warp beam. The manner in which this rotation takes place will be described at a later stage.

The shaft 32 carried in the machine frame and rotated by the loom drive also carries a disc cam 33 which coacts with the roller 36 supported on the end of the feeler lever 35 for rotation about the pivot point 34. The connecting rod 37 pivots on the same point, and is rigidly connected to the feeler lever 35 by the angle bracket 38, screws 40 entering in slots 39 in the angle bracket permitting setting of the angle between the two levers 35 and 37, which form a rigid angle lever 35/37. The other end of the connecting rod 37 is connected at the connecting point 41 to the link pin 42 and the latter at the connecting point 43 in the arm 44 of a lever collar 46 fixed on the shaft 45. The shaft or spindle 45 is in turn supported on two pivoting members 47 and 48 which are jointly pivotable about the axis of pivot 49 carried at both sides of the rear part of the machine frame between the pivots of the double-sheet bearing plates 21a and 21b. On the axis 45 is carried the lever 50 connected with the one end of the link pin 51 whereas the other end of this link pin 51 is connected to the bearing lever 52, the other end of which rotates freely

about the axis of pivot 49 of the elements 47/48. Corresponding to the link pin 51 and the bearing lever 52 on the other side of the machine frame (FIG. 4), a similar link pin 53 and a similar bearing lever 54 are provided, the free end of the link pin being connected to an arm 55 corresponding to the arm 50 and arranged to rotate about the axis 45, whereas the free end of the bearing lever 54 is similarly disposed for rotation about the axis of pivot 49. The two bearing levers 52 and 54 have corresponding bearings 56 and 57, and 58 and 59, respectively, carrying the shaft 60 of the principal whip roll 61 and the shaft 62 of an auxiliary whip roll. An additional fixed guide roll 89 is mounted underneath the auxiliary whip roll 63 and disposed in the path of the warp threads between the warp beam and the auxiliary whip roll in such manner that the warp 76 runs from the warp beam 1 over the guide roll 89, the auxiliary whip roll 63 and the principal whip roll 61.

The result of this arrangement is that the bearing levers 52 and 54, as well as the principal whip roll 61, are incorporated in two separate transmission systems, and thus influenced by two different mechanical linkages. Thus, the eccentric disc cam 33 causes the rigid, two-armed lever 35/37 to swing about the pivot 34 and thus through the intermediary of the pushrod 42 causes the lever collar 46 with the pivot 45, and thereby through the levers 51 and 53 also the bearing levers 52 and 54 with the principal roll 61 and the auxiliary roll 63, to swing aside. A similar, swinging displacement of this system can, however, also be performed by the swinging arms 47 and 48, viz., in such manner that a rotation of these arms about the pivot 49 through their associated spindle 45 and the arms or levers 50 and 55, as well as the rockers 51 and 53, correspondingly rocks the bearing levers 52 and 54 about their pivot 49. A turning moment is further exerted on the swinging arms 47 and 48 by the weight 64 which is connected by the steel band 66 passing over the guide-roller 65 with a drum 67 carried on the control shaft 22. The swinging arms 47 and 48 each have an opening or port 68 and 69 respectively, with internal teeth, 70 and 71; the control shaft passes through these openings or ports and mounts gear wheels 72 and 73 meshing with the aforesaid internal teeth 70 and 71 respectively. As a result, the weight 64 in FIG. 3 exerts a clockwise turning moment on the swinging arms. The swinging arm 47 is further associated with a damping device essentially consisting of a piston or plunger 74 and a cylinder 75, having a specific, specially selected, damping characteristic (see FIG. 8). The hollow plunger 74 has, below the port 74a, a built-in valve 81 urged from below by the spring 82 against its seat 83 for the purpose of closing the port 88. The plunger head 84 is slidably arranged within the cylinder 75 and penetrated by a bore 85. An overflow or bypass is indicated at 86a. The damping device thus comprises two spaces or chambers, viz. a first chamber 86 comprising the space over the plunger head 84 and communicating with the space formed by the hollow portion of plunger 74 through the port 74a; and a second space or chamber 87, below the valve 81 and plunger head 84. The two chambers 86 and 87 are continuously in communication through the bore 85 and, when the valve is open, through the port 88. In the opening position, both chambers 86 and 87 are filled with a working fluid, e.g. oil. If the plunger is now drawn upwards, a pressure-drop occurs in the chamber 87, the valve 81 opens the port 88, and pressure-equalization takes place between the two spaces or chambers without perceptible retardation of the upward motion, through the aforesaid port. When the plunger is driven inwards, on the other hand, the valve 81 is forced by the pressure rise in the chamber 87 against its seat 83, so that the equalization of the pressure between the spaces or chambers 86 and 87 now takes place solely through the bore 85. Conse-

quently, slow, descending motions of the plunger can take place without any substantial retardation or braking effect; while more abrupt downstrokes, exceeding a certain speed, are effectively braked or damped.

The motions of the bearing levers 52, 54, deriving from the disc cam 33, and those imparted by the swinging arms 47, 48, are not to be allowed to influence each other. This condition is only fulfilled when the two circular arcs described from the centers 41 and 49 through the hinge point 43 are practically coincident through a sufficiently large range. In the arrangement represented here, this is attained to a practically sufficient extent by placing the two centers 41 and 49 very close together, so that the circular arc described during rotation of the disc cam 33 from the center 34 through the hinge point 41 cuts the axis 49, the pin 41 swinging about this intersection point approximately equally in either direction; and, further, by seeing to it that the tangent to the said arc in this point of intersection coincides with the direction of motion of the pushrod 42, when the swinging arms 47, 48 are in the midposition, i.e., slightly lower than shown in FIGS. 3 and 4.

From this description of the arrangement it will be seen, omitting from consideration the control action of disc cam 33 which merely represents an additional refinement, that the swinging arms 47 and 48 on the one hand receive a turning moment M imparted by tension of the warp threads 76 running over the principal whip roll 61 and the auxiliary whip roll 63, and wound on the warp beam 1, through the intermediary of the bearing levers 52 and 64, the link pins 51 and 53, and the arms 50 and 55; and on the other hand are acted upon by an opposed, constant torque B , exerted by the weight 64 through the gear wheels 72 and 73. In the always self-adjusting equilibrium position, $M=B=\text{const}$. However, the relationship $M=K(a-b)$ (see FIG. 5) also applies, in which K is the warp tension (it is assumed for the sake of simplicity that the two forces acting on the assembly formed by the principal whip roll and the auxiliary whip roll, in the direction of the warp threads running off the principal whip roll, and in the direction of the warp threads running on to the auxiliary whip roll, are equal), a the distance of the warp threads running off and b the distance of the warp threads running on, from the common axis of rotation 41. In other words,

$$K = \frac{B}{a-b}$$

i.e., is inversely proportional to the difference of the two, above-named distances; so that the warp tension can only be held constant if within the potential range of swing of the principal and auxiliary whip rolls, the difference $a-b$ can be held constant at least approximately. By the manner selected of supporting the principal whip rolls 61 and the auxiliary whip rolls 63 in the same bearing levers 52 and 54, it has been possible to make the ratio of the geometric lever arms a and b such that the difference $(a-b)$ remains practically constant, despite rotation of the bearing levers and, additionally, in view of the provision of the fixed guide-roller or drum 89, substantially independent of the instantaneous diameter of the warp beam. In order to enable a prescribed warp tension value to be adjusted at any time without difficulty, a suitable relationship must be established between the tensioning weight and the tensioning force on the warp threads. In the exemplary embodiment shown, this transmission ratio has been fixed at 1:10, for which reason, in view of the restricted space available, internal gearing has had to be used for the swinging arms 47, 48 ($B(a-b)=10G$). Accurately dimensioned slab weights of 5, 2, 1 and 0.5 kg. enable in practice and adjustment of the warp tension to be obtained, variable stepwise in units of 5 kg. If, for example, the warp tension is too low, and $M < B$, then the swinging arms together with the principal whip roll 61 and the auxiliary whip roll 63, in

FIG. 3, rotate clockwise, whereby the warp is tensioned, the turning moment M increases, and the displacement of the whip roll assembly ceases only when equilibrium has been established between the two turning moments, and the required warp tension, as adjusted by the dimensioning of the loading weights, has become established. At the same time, this rotatory displacement remains substantially unaffected by the damping device 74/75 since it causes the plunger 74 to move outwards, which, as already explained, takes place practically without resistance. If, from this equilibrium condition, the warp tension rises further during weaving, and consequently $M > B$, the whip roll 61 swings, i.e. the arms 47 and 48 in FIG. 3 turn anticlockwise, which swinging motion, however, depending on the speed with which it takes place, is braked or retarded by the damping device 74/75. Should an occasional increase in the turning moment M be produced, for instance, by an inadequate advance of the warp-beam, the corresponding swinging motions of the arms 47 and 48 take place without encountering any substantial resistance, since such displacements and in fact all movements produced by the usual fluctuations of the warp tension take place only very slowly.

In the presence of abrupt and brief changes in the warp tension, such as those caused by the impacts of the batten, the damping device 74, 75 has an entirely different effect in that it completely brakes the swinging arms, so that the impacts of the batten cannot cause any displacement, either of the swinging arms 47, 48, the whip roll 61, or the weight 64.

As a result, the arrangement described, enables the swinging arms to be locked in the case of an abrupt and brief rise of the warp tension, while a slow, gradual increase in the warp tension causes the swinging arms 47, 48 in FIG. 3 to turn counterclockwise. This motion, acting through the internal gears 70 and 71 and the gear wheels 72 and 73, causes a rotation of the control shaft 22, viz., in FIG. 3 counterclockwise and in FIG. 4 clockwise. As already mentioned earlier, such a rotation of the control shaft displaces the sliding block 26 (FIG. 4) to the left and thereby moves the control-rod pin 20a inside the guide block 27, viz. in FIG. 4, to the right. This increases the distance between this pin 20a and the pivot pin 26a, and, consequently, the length of stroke of the up and down motion of the control rod 20, whereby, as already stated, the forward feed advance of the warp beam is also increased. This causes the run-off of the warp 76 from the warp beam 1 to become greater, so that the warp tension and thereby also the turning moment M are diminished. A contrary motion of the swinging arms 47 and 48 and therewith of the whip roll 61, produced by the action of the weight 64, now restores the equilibrium of the system. Thus, in the arrangement described, the whip roll, which is made to perform controlled motions for the purpose of balancing the warp tension when the shed is opened and closed, is also movably supported in such manner as to be able to control the warp tension, and finally, on the occurrence of the abrupt but very brief rise in tension caused by the impacts of the batten, behaves practically as if it were fixed in place.

In addition, however, the whip roll can also be separately controlled by the action of the disc cam, viz. through the intermediary of the levers and guides 35, 37, 42, 44, 50/53, in particular, under the condition already stated, concerning the reciprocal positions of the track of the hinge point 41 and the axis of rotation 49.

Such a positive control of the whip roll is particularly desirable in regard to the need both for balancing the warp tension when the shed is opened and closed and for providing a strong warp holding during the impacts of the batten. In the first instance, the fluctuations in the thread tension produced by the opening and closing of the shed are smoothed out; in the second case, a strong holding of the warp is ensured when the reed of the batten is beating up the weft to the fell of the cloth.

FIG. 6 shows a correspondingly profiled disc cam or cam plate 33, and FIG. 7 the curve of the force exerted thereby on the whip roll assembly during two revolutions of the cam shaft, in relation to the angular displacement of this cam plate. The circular segment portion of the cam profile 77 produces no additional action on the whip roll assembly; the cam segment 78 produces at the instant of closing the shed a steadily increasing swing of the whip roll assembly, in FIG. 3 clockwise, about the pivot point 49, i.e. an increasing pull on the warp until the shed 79 has closed; while the segment 80 finally exerts a brief counter-pull synchronised with the reed beating the weft.

Thus, the invention succeeds in providing a whip roll assembly adapted for being positively controlled to compensate for the shedding action, which is yieldably, or displaceably, supported so as to be capable of controlling a mechanically driven warp beam, and considering a different aspect, a whip roll arrangement of this kind which is subject to an additional positive control whereby to ensure a substantially constant tension of the warp, capable of being regulated to a predetermined, absolute value.

Although one embodiment of my invention has been described in detail with reference to the accompanying drawings, I wish it to be understood that various changes in the shape, sizes and arrangement of parts can be resorted to within the scope of the appended claims and without departing from the spirit or sacrificing the advantages of the invention.

I claim:

1. A loom including a warp beam and a warp tension control device which comprises a bearing means supported for rocking and pivotal displacement, a principal whip roll having an axis extending in parallel to the axis of the warp beam, mounted on said bearing means, and an auxiliary whip roll having an axis extending in parallel to the axes of the principal whip roll and the warp beam, mounted on said bearing means and disposed in the path of the warp threads fed from the warp beam to the principal whip roll, between said warp beam and said principal whip roll.
2. A loom including a warp beam and warp tension control device which comprises a bearing means supported for rocking and pivotal displacement, a principal whip roll having an axis extending in parallel to the axis of the warp beam, mounted on said bearing means, an auxiliary whip roll having an axis extending in parallel to the axes of the principal whip roll and the warp beam, mounted on said bearing means and disposed in the path of the warp threads fed from the warp beam to the principal whip roll, between said warp beam and said principal whip roll, and a fixed guide roll having an axis extending in parallel to the axes of the warp beam and the principal and auxiliary whip rolls, disposed in the path of the warp threads fed from the warp beam to said auxiliary and principal whip rolls, between said warp beam and said auxiliary whip roll.

3. A loom including a warp tension control device according to claim 2, wherein a plane through the pivotal axis of the bearing means and the axis of the principal whip roll, extends at substantially right angles to the plane in which the warp threads run off the principal whip roll, and a plane through the pivotal axis of the bearing means and the axis of the auxiliary whip roll, extends at substantially right angles to the plane in which the warp threads travel from the fixed guide roll to the auxiliary whip roll.

4. In a loom including a warp tension control device according to claim 2, a warp beam feed control device comprising swinging arms connected with said bearing means, and a damping device adapted to yield to slow variations in the warp tension but to effectively brake said warp beam feed control device in response to sudden variations in the warp tension.

5. A device according to claim 4, wherein said damping device is provided as a hydraulic mechanism including a piston, a check valve controlled main passage in said piston, and a narrow bore also in said piston, chambers above and below said piston, and working fluid adapted to pass from one to the other of said chambers through the said passage and said bore, respectively.

6. A device according to claim 4, comprising a weight influencing said swinging arms, the turning moment imparted by said weight to said swinging arms being opposed to the turning moment imparted to the swinging arms by said bearing means in response to the warp tension.

7. A device according to claim 4, wherein the bearing means and the swinging arms pivot about the same axis.

8. A device according to claim 4, wherein the swinging arms comprise internal gears, a shaft controlling the feed of the warp beam, and gears on said shaft meshing with said internal gears.

9. A device according to claim 8, comprising a weight influencing the swinging arms, and a drum mounted on the shaft controlling the feed of the warp beam, said weight acting directly on said drum.
